DESIGN FOR A COMBINATION RAZOR AND BLADE SHARPENER

Shelley W. Ford, Dayton, Ohio

Application May 24, 1943, Serial No. 110,274

Term of patent 7 years

To all whom it may concern:

Be it known that I, Shelley W. Ford, a citizen of the United States, residing at Dayton, in the county of Montgomery and State of Ohio, have invented a new, original, and ornamental Design for a Combination Razor and Blade Sharpener, of which the following is a specification, reference being had to the accompanying drawing, forming a part thereof, wherein:

combined razor and blade sharpener constituting my new design;

Figure 2 is a side elevational view; and

I claim:

The ornamental design for a combination razor and blade sharpener, substantially as shown.

SHELLEY W. FORD.
